ATTORNEY.

UNITED STATES PATENT OFFICE.

FRANK CHALFANT, OF FORT WAYNE, INDIANA.

POST FOR COUCHES.

Application filed October 6, 1934. Serial No. 742,059.

The invention relates to resilient attachments for couches, cots, beds and the like, and it is particularly directed to resilient legs for ambulance cots designed for use in the conveyance of invalids.

The object of the invention is to provide means for couches and the like, by which the top is resiliently supported so that jars and bouncing of the carriage in transporting an invalid is not felt by him.

The invention consists in the novel construction and arrangement of parts herein-after described and set forth in the claims.

In the accompanying drawings an embodiment of the invention is illustrated and in which Figure 1 is a perspective view of a couch having the invention applied thereto and Fig. 2 an elevational view of the resilient leg, partly in section.

Referring to the illustrative embodiment of the invention the top 1 of the couch upon which a person may be placed, may have any suitable form. The frame of the top in the present illustration is formed of tubes 2 together with suitable cross-tubes to make it rigid. At the opposite ends of each tube 2 are T-unions 3 into the lower openings of which are threaded or otherwise secured the sleeves 4. Within each sleeve is a coiled spring 5, the upper end of which abuts the lower face of a plug 6 secured in or part of the upper end of the sleeve. The lower end of the spring engages the upper end of a leg 7, the upper end 8 of the leg being rounded to fit within the sleeve and the lower end of the sleeve being rounded inwardly after the head of the leg is inserted in the sleeve to prevent the unintentional withdrawal of the leg from the sleeve. A plug 9, preferably formed of felt or some other substance adapted to take up oil, is inserted within the lower end of the coiled spring and above the upper end of the leg 7. An oil hole 10 is formed in the sleeve adjacent the plug 9 through which oil may be admitted to saturate the plug. This plug therefore causes a lubrication of the interior of the sleeve.

The lower end of the leg is inserted into a union 11, a tube 12 being connected to the unions 11 on each side of the frame. A socket 13 is formed in the lower end of the

leg 7 for the reception of the spindle 14 of the castor 15, a ball 16 being disposed between the upper end of the spindle 14 and the end of the socket. A groove 17 is formed in the spindle into which is projected the inner end of a set screw 18 that is inserted through the wall of the union and the adjacent wall of the socket. It is apparent that the set screw prevents withdrawal of the leg 7 from the union 11 and also the withdrawal of the castor 15 from that union, but permits rotation of the spindle 14 in the socket.

It will be noted that the leg below the upper end is less in diameter than said upper end. This feature permits the sleeve to descend without binding on the leg when it may be out of line with said leg by reason of an extra weight being applied to the top over the sleeve or by a sudden jar on the castor beneath the leg.

From the foregoing, it will be apparent that the weight of the top of the device is carried by the springs 5, and that any added weight on the top will cause the sleeves to descend and compress the springs 5 more or less. Any jar on the couch applied at the castors will be taken up by the springs 5 so that the top will be unaffected thereby.

What I claim is:

1. In an article of the class described, a top frame, a wheeled lower frame and a plurality of vertical members resiliently connecting the two frames, each vertical member comprising a sleeve depending from the top frame, a leg secured in the lower frame and projecting upwardly into the lower open end of the sleeve, the leg having a head at its upper end slidably fitted within the sleeve, and the leg below said head being tapered and adapted to permit the sleeve to slide thereon at various angles relating to the longitudinal axis of the leg, and a spring within the sleeve to oppose relative longitudinal movement of the sleeve and the leg.

2. In an article of the class described, a top frame, a wheeled lower frame and a plurality of vertical members resiliently connecting the two frames, each vertical member comprising a sleeve depending from the top frame, an upstanding leg secured at its

lower end to the lower frame and having a head at its upper end slidably fit within the sleeve, the leg beneath the said head being less in diameter than the lateral diameter of the head, a coiled spring within the sleeve to oppose relative longitudinal movement of the sleeve and the leg and a lubricant-carry-

ing member carried by the spring and adapted to lubricate the sleeve.

In witness whereof I have hereunto subscribed my name this 19th day of September, 1924.

FRANK CHALFANT.
